UNITED STATES PATENT OFFICE.

HARRY A. CHANDLER, OF SIOUX CITY, IOWA.

CONVERTIBLE VEHICLE BODY.

Application filed April 6, 1927. Serial No. 181,401.

My invention relates to convertible vehicle bodies of the type illustrated and claimed in my prior Patent Number 1,627,833 May 10, 1927, and the primary object of 5 the present invention is to improve upon and simplify the construction illustrated in that application.

More specifically, the present invention has for its aim to obtain the extension of 10 the side of the vehicle in a single operation instead of several. To that end, the doors and intervening posts are carried by a swinging, extensible casing, which is hinged to the vehicle body on an axis closely adjoining the axis of the rear door where the rear door is of the type hinged at its rear edge, 15 the forward portion of the casing being free to swing laterally and positive controlling means being provided to obtain such lateral 20 swinging.

Another object of the invention is to obtain a casing, as described in the preceding paragraph, and to construct this casing with relatively thin sheet metal upper and lower 25 walls, whereby the edges of said walls will be substantially invisible when the casing is in its inner position, registering with the normal lines of the vehicle body.

Another object is to provide means for 30 removably connecting the intermediate post between these thin sheet metal walls in such a manner that, when connected, the post may be locked tightly at its ends against both of the walls in order to aid in bracing the walls 35 against sagging and to form a more rigid structure.

A further object of the invention is to 40 provide a simple device for propelling the casing away from and toward the body of the vehicle, as has already been mentioned, 45 said device being attached to accomplish its function in such a manner as to insure against binding of the casing against the vehicle body by maintaining the casing in correct plumb, said means including an operating handle conveniently located for operation and yet in a position not to be in the way at any time.

A still further object of this invention is 50 to obtain a novel method of attaching the forward wall to the casing when in extended position and locking it securely in place without the use of bolts or the like, thereby obtaining the desired result seen in the invention of my co-pending application, hereinbefore referred to of having the forward

wall removable so that, when the casing is in its normal inner position, this forward wall will not extend into the vehicle to obstruct the vision and otherwise be in the way. 60

With these and other objects in view, my invention consists in the construction, arrangement and combination of the various parts of my device, whereby the objects contemplated are attained, as hereinafter more 65 fully set forth, pointed out in my claims, and illustrated in the accompanying drawings, in which:

Fig. 1 is a horizontal, sectional view through the extensible side of a vehicle employing my invention. 70

Fig. 2 is a similar view showing the casing extended, one of the doors being partially removed to show the hinged connection of the casing. 75

Fig. 3 is a perspective view of the forward portion of the casing in extended position, the forward wall being shown in the process of being attached.

Fig. 4 is a vertical, sectional view taken 80 on the line 4—4 of Fig. 1.

Fig. 5 is a detail, sectional view taken on the line 5—5 of Fig. 4.

Fig. 6 is a detail, sectional view taken on the line 6—6 of Fig. 5. 85

Fig. 7 is a detail, sectional view through one of the horizontal walls of the casing, illustrating the intermediate post and its connecting mechanism.

Fig. 8 is a detail, sectional view taken on 90 the line 8—8 of Fig. 7, the post not being shown.

Fig. 9 is a detail, sectional view taken on the line 9—9 of Fig. 4.

Fig. 10 is an elevation taken as indicated 95 by the line 10—10 of Fig. 4.

In my co-pending application, referred to, I have described the advantages of a vehicle which may be converted from a passenger automobile to a casket coach by extending 100 one side to a position parallel with the axis of the vehicle. The extending is done in the construction of that application by individually extending intermediate post, which separates the doors of the vehicle, and the 105 hinges, which carry the forward door in order that they may be brought into alignment in the proper extended position.

The extending of the post and forward door hinges comprise two separate operations and in addition to these, it is necessary to insert a pair of flaps or sheet metal 110

walls in horizontal positions at the upper and lower extremities of the forward door in order to close the space which will be formed between the upper and lower edges 5 of the door and the vehicle body door frame. This adds two more operations to the task of converting the vehicle from one type of body to the other and in addition there is the necessity of attaching a forward wall to 10 the hinges of the forward door to close the space between the forward door and the vehicle body. My present invention contemplates forming a unitary casing including upper and lower walls and a forward connecting portion, the forward door and intermediate post being permanently carried by the casing so that the extension of the casing serves to extend the doors and posts together with the casing. Thus the five operations 15 originally described will be reduced to a single operation and the added operation of securing the forward wall in place will make a total of two steps necessary for the conversion of the vehicle.

25 I have used the reference character 10 to indicate the rear side wall of the vehicle and the reference characters 11, 12, 13, and 14, respectively, to indicate the forward door post, the wind shield, the floor and the top, 30 respectively, of the vehicle.

An ordinary form of control lever for the wind shield is shown at 15 in Fig. 4.

The extensible casing comprises the upper panel 16, (Fig. 4), the lower panel 16^a and 35 the forward connecting post 17, which is comparatively thin, being just sufficiently heavy to insure proper strength and rigidity. It will be noted that the post 17 is positioned in a plane extending transversely of the vehicle and that when the casing is in its closed position, that the post 17 will lie flush 40 against the forward face of the post 11.

Rigidly secured to the post 17, at its upper and lower ends, and extending inwardly, are 45 the extension arms 18 and 18^a. The arms are slidably mounted in dove-tailed slots 19 in blocks 20, which are secured to the post 11, (Figs. 4 and 6).

The forward door 21 is hinged at 22 to 50 the post 17, and at the upper and lower ends of the door, the hinges 22 may be formed directly on the ends of the arms 18 and 18^a.

It will be noted that the upper panel 16 is supported by the upper extension arm 18 by means of an angle plate 23, (Fig. 4). This is to prevent sagging of the upper plate and to form a rigid construction. The angle plate 23 is secured to the arm 18 and the wall 16 slides against the plate 23 as the 55 casing is moved from one position to another. This is necessary as will later be apparent when the connection of the arms 18 and 18^a with the vehicle post 11 is considered.

The lower panel 16^a rests against the floor 60 of the vehicle at all times, (Figs. 1 and 2),

and may or may not be connected to the extension arm 18^a in this manner. The arm 18^a may be formed with a hinge 24, dividing it into two portions, the longer of which extends within the vehicle when the casing 70 is in closed position and which may be pushed forwardly, as shown in Fig. 5, to a position out of the way. The actuating mechanism comprises a shaft 25, journalled in gear boxes 26, secured to the box 11 and 75 provided within said gear boxes with drive pinions 27, which engage rack teeth 28^a on the forward faces of the extension arms 18 and 18^a respectively. The shaft 25 is rotated by means of a worm 28, meshing with 80 a work wheel 29 on the shaft 25 within a worm housing 30. A crank 31 has a flattened portion 32, which engages a screw driver slot 33 in the shaft of the worm 28 and is attachable to the worm shaft in this 85 manner when it is desired to rotate the same.

The housing 30 is secured to the instrument board 34 of the vehicle for convenient operation. It will now be seen that rotation of the crank 31 in engagement with the 90 worm 28 will cause the shaft 25 to rotate, thus extending the arms 18 and 18^a, the latter carrying the casing from closed to open position or vice versa. As the casing swings, the intermediate post 35, which separates the 95 doors 21 and 36, will be swung substantially on an arc concentric with the axis 37 of the rear door 36 and the latter will thus remain in engagement with the post. There will be some tendency for the post and door to pull 100 apart, due to the offsetting of the axis 38 of the casing, but not sufficient to destroy the latching engagement of the door with the post.

The panels 16 and 16^a are shaped so that 105 when the casing is in closed position, their outer edges will conform to the contour of the vehicle body and when in extended position their inner edges will overlap the floor 110 13, as shown in Fig. 2, thereby forming a snug joint at all times between the vehicle casing and the body.

The intermediate post 35 is removable for the purpose of allowing a casket to be inserted into the vehicle from the side. I provide means for rigidly connecting the post 115 to the walls 16 and 16^a as follows:

To the panels 16 and 16^a are secured loops 39, shown in Figs. 7 and 8, and slidably mounted within the post 35 is an arm 40, 120 having a hook 41, its upper end projecting beyond the side of the post and adapted to enter the loop 39. The arm 40 is pulled downwardly by means of an eccentric cam 42 forming part of the shaft 43, journalled 125 in the post 35 and rotated by means of a lever 44. The arm 40 has an eccentric bearing 45, encircling the cam 42 and as the lever 44 is moved upwardly, the arm 40 will be pulled downwardly, thereby engaging the 130

loop 39 and pulling the wall 16 tightly against the upper end of the post 35. An identical construction is provided for the lower end of the post.

5. In order to close the space between the post 17 and the post 11 when the casing is extended, I provide the forward removable wall plate 46, which is curved at its outer edge, as at 47, to cover the hinges 32 and 10 which is provided at its inner edge with a flange 48, adapted to bear against the post 11 and to be locked thereagainst by means of latch buttons 49. The upper and lower edges of the forward wall plate 46 are channeled as at 50 and the forward edges of the panels 16 and 16^a are bent upwardly and downwardly to form flanges 51, (Fig. 6), which receive the channels 50 for attaching the plates 46 to the casing. It will now be 15 seen that the plates 46 may be simply slid into place over the flanges 51 until the flanges 48 contact with the posts 11, whereupon the flanges may be locked against the posts by rotating the buttons 49 and the worm 28, 20 tightened to bring pressure of the hinge elements 22 against the curved portion 47 of the plates, thereby locking the plates under pressure against the buttons 49 and eliminating all loose connections which might cause 25 rattling.

Some changes may be made in the construction and arrangement of the parts of my invention without departing from the real spirit and purpose of my invention, and 30 it is my intention to cover by my claims, any modified forms of structure or use of mechanical equivalents, which may be reasonably included within their scope.

I claim as my invention:

40 1. In a convertible vehicle body, an extensible casing including two doors and an intermediate post, forming part of one side thereof, and hinged to the body on a vertical axis at its rear end, and including upper and 45 lower panels substantially flush with the ceiling and floor of the body and slidable therewithin.

2. In a convertible vehicle body, an extensible casing including two doors and an intermediate post, forming part of one side thereof, and hinged to the body on a vertical axis at its rear end, and including upper and lower walls substantially flush with the ceiling and floor of the body and slidable therewithin and extension arms slidably mounted upon the body and supporting the forward end of the casing.

3. In a convertible vehicle body, an extensible casing including two doors and an intermediate post, forming part of one side thereof, and hinged to the body on a vertical axis at its rear end, and extension arms slidably mounted upon the vehicle body and supporting the forward end of the casing, said arms being provided with rack teeth

and rotatable pinions journaled to the body and engaging said rack teeth for positively controlling the positions of the arms.

4. In a convertible vehicle body, an extensible casing including two doors and an intermediate post forming, part of one side thereof, and hinged to the body on a vertical axis at its rear end, and extension arms slidably mounted upon the vehicle body and supporting the forward end of the casing, 70 said arms being provided with rack teeth, rotatable pinions journaled to the body and engaging said rack teeth for positively controlling the positions of the arms, a vertical shaft carrying said pinions, and a worm and 75 worm gear drive for said shaft.

5. In a convertible vehicle body, an extensible casing including two doors and an intermediate post, forming part of one side thereof, and hinged to the body on a vertical axis at its rear end, and including upper and lower panels substantially flush with the ceiling and floor of the body and slidable therewithin, a relatively thin post connecting the forward extremities of said walls, 80 the end of the casing being hinged to the vehicle body on a vertical axis and extension arms slidably mounted upon the body and supporting said post.

6. In a convertible vehicle body, an extensible casing, including two doors and an intermediate post, forming part of one side thereof, and hinged to the body on a vertical axis at its rear end; upper and lower panels substantially flush with the ceiling and the 90 floor of the body, respectively, and slidable therewithin, a relatively thin post connecting the forward extremities of said panels, extension arms, provided with rack teeth, 95 slidably mounted upon the body and supporting the said post, and rotatable pinions journaled to the body and engaging said rack teeth for positively controlling the positions of the arms.

7. In a convertible vehicle body, an extensible casing including two doors and an intermediate post, forming part of one side thereof, and hinged to the body on a vertical axis at its rear end, and including upper and lower panels substantially flush with the 110 ceiling and floor of the body and slidable therewithin, and extension arms slidably mounted upon the vehicle body and supporting the forward end of the casing, said upper and lower panels having their outer 115 edges curved to register with the contour of the vehicle body when the casing is in closed position.

8. In a convertible vehicle body, an extensible casing including two doors and an intermediate post forming part of one side thereof, and hinged to the body on a vertical axis at its rear end, and including upper and lower panels substantially flush with the ceiling and floor of the body and 125

slidable therewithin, and extension arms slidably mounted upon the vehicle body and supporting the forward end of the casing, locking arms slidably mounted in the ends 5 of the intermediate post and having laterally projecting hooked ends, means for positively moving said arms toward the center of the post, and loops secured to the upper and lower panels in positions to be engaged by 10 said hooked ends.

9. In a convertible vehicle body, an extensible casing including two doors and an intermediate post, forming part of one side thereof, and hinged to the body on a vertical axis at its rear end, and including upper and lower panels substantially flush with the ceiling and floor of the body and slidable therewithin, and extension arms slidably mounted upon the vehicle body and supporting the forward end of the casing, the forward ends of the upper and lower panels being bent upwardly and downwardly to form vertical flanges, and an attachable forward wall having channels at its ends adapted to receive said flanges. 25

10. In a convertible vehicle body, an extensible casing including upper and lower casing members, an intermediate post and two doors, the casing forming part of one side of the body and being hinged thereto on a vertical axis at its rear extremity and adapted to be extended as an integral unit, the rear door being hinged to the body on a vertical axis, substantially coinciding with 30 that of the casing.

11. In a convertible vehicle body, an extensible casing including upper and lower casing members, an intermediate post and two doors, the casing forming part of one side of the body and being hinged thereto on 40

a vertical axis at its rear extremity and adapted to be extended as an integral unit.

12. In a convertible vehicle body, an extensible casing including upper and lower casing members, an intermediate post, two doors separated by said post and a relatively thin post connecting the forward extremities of said upper and lower casing members, the casing being hinged at its rear extremity to the body on a vertical axis and 45 adapted to be extended as an integral unit, and extension arms slidably mounted upon the body and supporting said relatively thin post. 50

13. In a convertible vehicle body, an extensible casing including upper and lower casing members, an intermediate post, two doors separated by said post and a relatively thin post connecting the forward extremities of said upper and lower casing 55 members, the casing being hinged at its rear extremity to the body on a vertical axis and adapted to be extended as an integral unit, said relatively thin post being received between the forward edge of the forward 60 door and the adjacent vehicle body post in a plane transverse to the axis of the vehicle when the casing is closed.

14. In a convertible vehicle body, an extensible casing including upper and lower 70 casing members, an intermediate post, two doors separated by said post and a relatively thin post connecting the forward extremities of said upper and lower casing members, the casing being hinged at its rear 75 extremity to the body on a vertical axis and adapted to be extended as an integral unit.

Signed this 1st day of April, 1927, in the county of Woodbury and State of Iowa.

HARRY A. CHANDLER.
